CLAIM

The ornamental design for a onesie, as shown and described.

DESCRIPTION

FIG. 1 is a perspective front view of a onesie showing my new design;

FIG. 2 is a perspective rear view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a close-up view thereof, as referenced in FIG. 1;

FIG. 10 is another close-up view thereof, as referenced in FIG. 2;

FIG. 11 is an environmental view of the onesie of FIG. 1 being worn and closed; and,

FIG. 12 is an environmental view of the onesie of FIG. 1 being worn and partially opened.

The broken lines in the drawings showing the onesie illustrate the portions of the onesie that form no part of the claimed design.

The partial human figure shown in broken lines is environmental subject matter included to illustrate how the design may appear when worn and forms no part of the claimed design.
